UNITED STATES PATENT OFFICE

JOSEPH GARIGLIO, OF NEW YORK, N. Y.

SAFETY ATTACHMENT FOR EXTRACTORS

Application filed November 29, 1927. Serial No. 236,522.

This invention relates to laundry machinery and has particular reference to a safety attachment for use in connection with extractors for drying clothes by centrifugal action.

The present invention broadly comprehends an improved means for positively preventing the opening of the extractor cover until the machine has reached a dead stop or the starting of the machine until the cover is completely closed so as to safeguard the operators or employees against injury.

The invention furthermore aims to provide a safe attachment of this character which is so constructed as to allow for manual turning 15 of the basket or inner rotary member of the extractor while the machine is out of operation with the cover open so that the operators may properly fill the basket or remove the contents therefrom.

20 The invention furthermore provides an improved safety attachment of the character set forth which is simple in its construction and mode of operation, which is economical to produce, and install, and which is highly 25 efficient and thoroughly reliable in its purpose.

With the above recited and other objects in view, reference is had to the following description and accompanying drawings in 30 which there is exhibited one example or embodiment of the invention, while the appended claims define the actual scope of the invention.

35 In the drawings—
Figure 1 is a top plan view of an extractor with the safety attachment applied and illustrating the machine in operation with the cover locked by the attachment in closed condition;

40 Fig. 2 is a front view thereof;
Fig. 3 is a fragmentary plan view with parts in section illustrating the extractor driving means in locked condition when the cover is opened;

45 Fig. 4 is a fragmentary sectional view taken approximately on the line 4—4 of Fig. 1 and illustrating respectively in full and dotted lines, the unlocked and locked conditions of the driving means;

50 Fig. 5 is an enlarged fragmentary sectional

view taken approximately on the line 5—5 of Fig. 1, illustrating the position of parts when the machine is in operation with the cover locked against opening;

Fig. 6 is a similar view illustrating the machine at rest with the parts in the shifted position by the opening of the cover;

Fig. 7 is a vertical fragmentary sectional view taken approximately on the line 7—7 of Fig. 5;

Fig. 8 is a fragmentary sectional view taken approximately on the line 8—8 of Fig. 5.

Referring to the drawings by characters of reference, A designates the body of the extractor which is of any of the usual types and having therein a basket or receptacle for the clothes, which basket or receptacle is driven by a suitable mechanism, such as a belt and pulley, from a drive pulley B on a countershaft C supported in bearings D—D which are carried by brackets E—E. The shaft C has secured thereto a live pulley F and a dead or idle pulley G, the former being keyed to the shaft and the latter loosely mounted on the shaft. A belt H trained around an overhead driving pulley is adapted to be respectively shifted from the live pulley to the dead pulley, or vice versa, by a shift rod I having a loop J through which one lead of the belt 60 H is trained. The shift rod is connected with a bell crank K fulcrumed at L and provided with an operating handle M. The shift rod is guided by a bracket arm N to which it is 65 slidably connected by a bolt or other equivalent device O operating in a slot P in the bracket arm N.

The extractor body which is provided with an open upper end has a cover Q which is connected to the body by a hinge having hinge knuckles R attached to the cover and hinge knuckles S attached to the extractor body. The hinge knuckles R are secured to a hinge shaft T while the shaft is free to turn in the body hinge knuckles S.

90 The safety attachment comprises a locking bolt 10 which is connected with the hinge shaft T in such a manner that when the cover Q is closed, the free end 11 which is guided 95 and received in an opening 12 in the

bracket arm N is retracted and when the cover is opened with the machine at rest, the free end 11 is projected into a keeper opening 13 in the shift rod I, it being understood that the shift rod at this time is disposed in a shifted position which brings the keeper opening 13 into alignment with the opening 12. The connection between the hinge shaft T and the lock bolt 10 preferably embodies an eccentric pivotal connection 14 with a circular disk or flange 15 secured to the hinge shaft T. It is obvious that while the cover Q is blocked against opening by the bolt 10, being prevented from rearward movement due to its engagement with the shift rod I while the same is shifted to a position to hold the belt H on the live pulley F, there is nothing to prevent the opening of the cover while the machine is still turning by momentum after the shifting of the belt H on to the dead pulley G. In order, therefore, to further safeguard the operator or employee from injury due to opening of the cover until the machine has come to a complete rest or dead stop, the opposite end of the hinge shaft T has keyed or otherwise attached thereto a locking member 16 having a tooth or pawl 17 projecting radially therefrom. The tooth or pawl is disposed between the furcations 18 of the bifurcated or forked member 19, which bifurcated or forked member has pivoted between spaced bearing brackets 20, a lock lever 21 having a shoulder 22. The lock lever 21 is normally swung to a position to hold the shoulder 22 in engagement with the pawl or tooth 17 by a spring 23 and is positively prevented from being swung to a released position by a locking rod 24 which is connected with the lever 21 and with a foot 25 which is fulcrumed at 26 in bearings 27 on a bifurcated member 28. The bifurcated member 28 has furcations 29 provided with aligned openings 30 through which the countershaft C extends. A wheel 31 is keyed to the shaft C for limited independent turning movement by a key or keys 32 which are secured to the shaft and which engage in circumferential slots 33 in the axially projecting hub portions 34 of the wheel 31. The hub portions 34 fit within the furcation openings 30. In order to properly support and space the bifurcated members 19 and 28, a connecting rod 35 extends therebetween. The wheel 31 is provided with a plurality of radially projecting pointed teeth 37 which define therebetween notches 38.

When the shaft C is turning it is obvious that the teeth 37 will prevent the lock lever 21 from being moved to a released position which disposes the shoulder 22 out of the path of movement of the pawl or tooth 17 of the locking member 16. It is further obvious that when the shaft C comes to rest, the lever

21 may then be swung to a release position against the action of the spring 23 due to the fact that one of the notches 38 defined between the teeth 37 will allow for the swinging movement of the foot. If the apex or point of one of the teeth 37 should be disposed in a position to obstruct the movement of the foot 25, the keyed connection 32 and 33 will permit of a limited movement of the wheel with respect to the shaft C so as to dispose the next adjacent notch in a position to allow for movement of the foot 25.

In order to permit of the manual turning movement of the basket or receptacle in the extractor body A when the cover is opened, it will be observed that the lock lever 21 is provided with an arcuate depression 40 which allows for the swinging of the lever and the consequent movement of the foot 25 to an out-of-the-way position with respect to the star wheel 31. It is apparent that with the cover opened and the bolt 10 in a locked position with respect to the shift rod I as illustrated in Fig. 3, it is impossible to shift the belt H from the dead pulley G to the live pulley F, and it is therefore apparent that a safety attachment for machines of this character has been devised which is fool-proof and practically automatic in its operation.

What is claimed is:

1. The combination with an extractor including a body having an inner rotary member and a drive shaft with shiftable means for rendering the drive shaft and inner rotatory member active; of a safety attachment including a wheel secured to the drive shaft and having notches in its periphery, a detent means for preventing, when in one of its positions, the opening of the cover, and a shiftable foot connected with the detent means and movable into the peripheral notches of the wheel only when the wheel is at rest, for permitting of the shifting of the detent means to a release position, and means operable by the cover when opened for locking the shiftable means in its shifted position which renders the drive shaft and inner rotary member inactive.

2. The combination with an extractor including a body having an inner rotary member and a drive shaft with shiftable means for rendering the drive shaft and inner rotatory member active; of a safety attachment including a wheel secured to the drive shaft and having notches in its periphery, a detent means for preventing, when in one of its positions, the opening of the cover, and a shiftable foot connected with the detent means and movable into the peripheral notches of the wheel only when the wheel is at rest, for permitting of the shifting of the detent means to a release position, and means operable by the cover when opened for locking the shiftable means in its shifted position which renders the drive shaft and inner ro-

tary member inactive, said means including a bolt shiftable to an engaged locking position with the extractor driving mechanism when said mechanism is inactive, whereby to hold said mechanism inactive while the cover is open.

5 Signed at New York in the county of New York and State of New York this 28th day of November A. D. 1927.
